LOCKING DEVICE

Owen H. Griswold, Trenton, N. J., assignor to
 Kaiser Cargo, Inc., Bristol, Pa., a corporation
 of California

Application December 28, 1943, Serial No. 515,922

4 Claims. (Cl. 287—99)

This invention relates to landing gear for airplanes and particularly to improvements in locking the hinged members when the gear is extended. Although adapted especially for the purpose indicated, the invention may be utilized in other structures where a similar problem of securely locking an elbow joint is met.

In the landing gear of modern airplanes, the wheel supports or struts include pivotally connected sections, the lower of which is adapted to swing to and from extended position. When the plane is flying, the wheels are withdrawn into recesses provided for that purpose in the fuselage. When extended, the struts are often subjected to great tensile and compressive loads and should be securely locked to prevent inadvertent failure or folding of the struts. Heretofore it has been necessary to rely on latches or pins as locking devices. These are inherently weak, are subject to misalignment and slipping, and frequently jam because of accumulation of dirt and other extraneous material.

It is the object of the present invention to provide a simple and effective device which can be manipulated easily to lock or release the pivotal connection between the parts of a wheel strut and which avoids the difficulties attendant upon the use of latches for that purpose.

Another object of the invention is the provision of a locking device which, when actuated, effects the desired movement of the lower element of the strut and which is not affected by foreign matter, is not released by recoil or backlash under tensile or compressive loads, and eliminates necessity for latches or similar holding means.

Other objects and advantages of the invention will be apparent as it is better understood by reference to the following specification and the accompanying drawings, in which

Fig. 1 is a view in perspective of the joint with the locking device in locking position;

Fig. 2 is a similar view showing the operation of the joint;

Fig. 3 is a view in perspective showing another phase of the operation;

Fig. 4 is a vertical section through the joint showing the locking device in locking position; and

Fig. 5 is a transverse section through the joint with the locking device in locking position.

Referring to the drawings, 5 indicates the upper portion of a wheel strut which is secured to a hinge member 6 and articulated by means of pins 7 with a bracket 8 to which the lower

section of the wheel strut may be secured. When the members 5 and 8 are turned about the pins 7, the strut is folded as shown in Figs. 2 and 3, to lift the wheels from their supporting position to the position in which they are carried while the plane is flying. This movement is effected in the manner hereinafter described by the actuation of the device which locks the strut against such movement while it is in extended position.

To ensure effective locking of the joint, I provide two links 9 and 10 which are supported on pins 11 and 12 on the bracket 8 opposite the pins 7. The links 9 and 10 are pivotally connected by a pin 13 to a bifurcated link 14 which is of greater length than the links 9 and 10. The opposite end of the link 14 is pivotally connected by a pin 15 to a lug 16 secured to the hinge member 6. A rod 17 is pivotally connected at 18 to the link 14, and the latter may be actuated through the rod to effect movement of the links 9 and 10 and of the bracket 8. The rod 17 may be actuated by any suitable power mechanism such as a hydraulic motor (not shown).

When the axes of the upper portion 5 of the wheel strut and the bracket 8 are in alignment, the links 9, 10 and 14 are in locking position, as indicated in Figs. 1, 4 and 5. In this position, the links are in alignment and hence the strut is securely locked against movement about the pins 7. No tensile or compressive stress can effect the breaking of the joint so long as the links 9, 10 and 14 are held in this position. Hence, until the rod 17 is actuated, no movement of the parts can occur.

When movement is to be effected for the purpose of raising the wheels, the rod 17 is actuated through the mechanism provided for that purpose. The link 14 begins to swing upwardly, carrying with it the links 9 and 10. This movement immediately breaks the lock and simultaneously moves the bracket 8 pivotally about the pins 13 and the movement continues until the bracket has been carried to its uppermost position as shown in Fig. 3, where it is held until the rod 17 is actuated in the opposite direction to return the bracket to its original position with the links 9, 10 and 14 again in alignment to securely lock the joint. The movement of the bracket 8 is assured by reason of the difference in length between the link 14 and the links 9 and 10. Hence the bracket must move in the manner indicated whenever these links are swung from the position in which they are in alignment and lock the joint.

The structure as described has numerous advantages. All of the movement occurs about the

sturdy pins which may be made of sufficient strength to withstand any stresses to which they may be subjected. The device is easy and economical to manufacture, requiring only the reaming of holes and the fitting of the pins therein. The device is not affected by dirt or other accumulations which are readily wiped away by operation of the parts. There are no latches and consequently none of the disadvantages to which latches are subject, such as failure of alignment and hence difficulty in engagement when required. Furthermore the structure is much stronger with a given weight than any possible latch structure, and its operation is positive so that there can be no mishap through failure of a part to properly engage or disengage when required. When the parts are in locking position, there is no possibility of turning the two sections of the strut about their pivotal axis. The release and movement of the strut are nevertheless effected by a single operation of the hydraulic motor or other power mechanism employed to lift the wheels.

Various changes may be made in the form and arrangement of the parts as well as in the utilization of the locking device for other than its primary purpose without departing from the invention or sacrificing the advantages thereof.

I claim:

1. In an articulated joint, the combination of pivotally connected members, a locking device comprising pivotally connected links each pivotally mounted respectively on one of the members and adapted when in alignment to lock the joint, one of the links being longer than the other link 35

whereby when the links are actuated the members are caused to move about their pivotal axis, and means for actuating the links.

2. In an articulated joint, the combination of 5 pivotally connected members, a locking device comprising a pair of links pivoted on one of the members, a longer link pivotally connected to the pair of links and to the other member, the links when in alignment being adapted to lock the joint, and means for actuating the links whereby the members are caused to move about their pivotal axis.

3. In an airplane wheel strut, the combination of pivotally connected strut members adapted 15 when aligned to sustain tensile and compressive loads, a locking device comprising pivotally connected links each pivotally mounted respectively on one of the members and adapted when in alignment to lock the joint, one of the links being longer than the other link whereby when the links are actuated the members are caused to move about their pivotal axis, and means for actuating the links.

4. In an airplane wheel strut, the combination 25 of pivotally connected strut members adapted when aligned to sustain tensile and compressive loads, a locking device comprising a pair of links pivoted on one of the members, a longer link pivotally connected to the pair of links and to the other member, the links when in alignment being adapted to lock the joint, and means for actuating the links whereby the members are caused to move about their pivotal axis.

OWEN H. GRISWOLD.
